UNITED STATES PATENT OFFICE.

ALBERT A. STOLL, OF LOUISVILLE, KENTUCKY.

DESIGN FOR A WATER-PILLOW.

SPECIFICATION forming part of Design No. 25,786, dated July 14, 1896.

Application filed May 22, 1896. Serial No. 592,686. Term of patent 14 years.

To all whom it may concern:

Be it known that I, ALBERT A. STOLL, a citizen of the United States, residing at Louisville, in the county of Jefferson and State of Kentucky, have invented and produced a new and original Design for a Water-Pillow, of which the following is a specification, reference being had to the accompanying drawing, showing a perspective view thereof.

10 A represents the body of the water-pillow,

having the large central aperture B, and at the corners the inlet and outlet tubes C, closed by the stoppers D.

What I claim is—

15 The design for a water-pillow herein shown and described.

ALBERT A. STOLL.
